DESIGN FOR A COMBINATION GRIDDLER AND
BAKING DISH OR THE LIKE

Clyde A. Ovenshire, Berkeley, Calif.

Application May 27, 1946, Serial No. 130,127

Term of patent 14 years

(Cl. D44—1)

To all whom it may concern:

Be it known that I, Clyde A. Ovenshire, a citizen of the United States and a resident of Berkeley, in the county of Alameda and State of California, have invented a new, original, and ornamental Design for a Combination Griddle and Baking Dish or the like, of which the following is a specification, reference is had to the accompanying drawing forming part thereof, in which:

Figure 1 is a perspective view of a combination griddle and baking dish, embodying the present invention; the baking dish surface being uppermost; and

Figure 2 is a view in transverse vertical section, taken centrally of the device as shown in Figure 1.

I claim:

The ornamental design for a combination grid-

dle and baking dish or the like, substantially as shown.

CLYDE A. OVENSHIRE.
